DESIGN FOR A DOLL

Isabel Manning Hewson, New York, N. Y.

Application February 10, 1945, Serial No. 117,870

Term of patent 14 years

(Cl. D34—2)

To all whom it may concern:

Be it known that I, Isabel Manning Hewson, a citizen of the United States, residing at New York, in the county of New York and State of New York, have invented a new, original, and ornamental Design for a Doll, of which the following is a specification, reference being had to the accompanying drawing forming a part thereof.

I claim:

The ornamental design for a doll, as shown.

ISABEL MANNING HEWSON.
